INVENTOR

UNITED STATES PATENT OFFICE.

WILLARD R. EVANS, OF KANSAS CITY, MISSOURI.

DESIGN FOR A TOY ARTIFICIAL BIRD OR FOWL.

46,726.

Specification for Design.

Patented Dec. 8, 1914.

Application filed May 2, 1914. Serial No. 836,029. Term of patent 3½ years.

To all whom it may concern:

Be it known that I, WILLARD R. EVANS, a citizen of the United States of America, residing at No. 4003 Prospect avenue, in the city of Kansas City, in the county of Jackson and State of Missouri, have invented a new, original, and ornamental Design for Toy Artificial Birds or Fowls, of which the following is a specification, reference being had to the accompanying drawing, forming part thereof.

The figure is a perspective view of a toy artificial bird or fowl showing my new design.

I claim:

The ornamental design for a toy artificial bird or fowl, as shown.

WILLARD R. EVANS.

Witnesses:

EUGENE E. BOWERS,
FRED H. EVANS.
